UNITED STATES PATENT OFFICE

106,652

DESIGN FOR A CONTAINER FOR COSMETIC PREPARATIONS

Benjamin F. Conner, West Hartford, Conn., assignor to Colt's Patent Fire Arms Manufacturing Company, Hartford, Conn., a corporation of Connecticut

Application April 27, 1937, Serial No. 68,999

Term of patent 14 years

To all whom it may concern:

Be it known that I, Benjamin F. Conner, a citizen of the United States, residing at West Hartford, in the county of Hartford and State of Connecticut, have invented a new, original, and ornamental Design for a Container for Cosmetic Preparations, of which the following is a specification, reference being had to the accompanying drawing, forming part thereof.

On the drawing:

Fig. 1 is a plan view of a container for cosmetic preparations embodying my new design.

Fig. 2 is a side view thereof.

The stippled and unstippled portions of the drawing are intended to represent different colors, but not any particular colors. The dominant feature of my design consists of the general shape or configuration of the container combined with the contrasting colors at the top and bottom.

I claim:

The ornamental design for a container for cosmetic preparations as shown and described.

BENJAMIN F. CONNER.
